UNITED STATES PATENT OFFICE.

CARL ROBERT VIEHOFER, OF BERLIN, GERMANY.

CORSET-FASTENING.

SPECIFICATION forming part of Letters Patent No. 472,087, dated April 5, 1892.

Application filed December 10, 1890. Serial No. 374,234. (No model.)

To all whom it may concern:

Be it known that I, CARL ROBERT VIEHOFER, a subject of the King of Prussia, German Emperor, and a resident of Berlin, in the German Empire, have invented certain new and useful Improvements in Corset-Fastenings, of which the following is a full, clear, and exact description.

The object of the present invention is to provide a corset-fastening which can be easily closed or unclosed under the bodice of the dress—that is, without first having to unbutton said bodice. I attain this object by dispensing with the buttons and slits or holes arranged in the corset-steels, and in use up till now, and substituting therefor a bolt and spring-clasps, arranged as hereinafter described, and illustrated in the accompanying drawings, in which—

Figure 1 is an elevation of one of the corset-steels forming the fastening. Fig. 1^a is a section on line *x x* in Fig. 1. Fig. 2 is an elevation of the other corset-steel, and Fig. 2^a a section on line *y y* in Fig. 2. Fig. 2^b is a part

side elevation of Fig. 2.

To the steel A are riveted the spring hooks or catches *a a*, the form of which may be clearly seen from Figs. 1 and 1^a. To the other corset-steel B are attached the locks *b*, which are constructed in the following manner: Referring to Fig. 2, a bridge or casing *b* is attached to the steel, having its front side open for the reception of the spring-hook *a*. Its opposite side, however, is bent round, forming a stop which prevents the hook *a* from penetrating too far through the lock. Attached to the steel inside the lock is the catch *d*, consisting of a projecting metallic piece having an inclined surface, Fig. 2^a, over which the hook slides on being inserted in the lock, and a vertical side, which arrests the said hook after its spring-point has passed behind it. The number of such locks and hooks arranged on the steels is optional and varies with the length of the corset.

Sliding vertically on the steel B and passing through all the locks arranged thereon is

a rod or rather bolt *c*, which bolt may be operated up or down by the steel by means of a lever *f*, also pivoted on the steel, and provided at its one end with a slit which incloses a pin of the bolt *c*. This bolt *c* is provided with projections *e e*, one at each lock. These projections, when the corset is closed, take the position shown in Fig. 2—*i. e.*, above the locks. 55

The corset is manipulated in the following manner: To close the corset the spring-hooks *a* of the steel A are inserted into the locks *b* of steel B, when the hooks will be compressed past the projections *d d*, and on having passed the same will spring behind them, holding the corset tightly closed. If it is required to open the corset, the lever *f* should be raised, whereby the bolt *c* will be slid down the steel, the projections on the same will pass into the locks behind or under the hooks *a a*, compressing the same, when the corset, owing to the pressure of the waist inside, will open. On closing the corset the bolt *c* must first be raised again and the hooks inserted in the locks, as hereinbefore described.

Having now particularly described and ascertained the nature of my invention and the manner in which the same is performed, I declare that what I claim, and desire to secure by Letters Patent, is—

In a corset-fastening, the steel bar A, provided with the spring-catches *a a*, in combination with steel bar B, provided with locks *b b* for reception of said spring-catches, having projections *d d*, with inclined side toward the spring-catches and vertical rear side for retaining same, with sliding bar *c*, provided with projections *e e*, having inclined surfaces and adapted on opening the fastening to engage under the hooks *a a*, said steel B having further a bolt-operating lever *f* pivoted thereto, substantially as described.

In witness whereof I hereunto set my hand in presence of two witnesses.

CARL ROBERT VIEHOFER.
